UNITED STATES PATENT OFFICE.

FRED L. MILLS, OF OAK PARK, ILLINOIS, ASSIGNOR TO MILLS NOVELTY COMPANY, OF CHICAGO, ILLINOIS, A CORPORATION OF ILLINOIS.

SAFETY-CATCH DEVICE.

Application filed January 11, 1926. Serial No. 80,589.

The present invention relates particularly to a safety catch device for use in connection with coin-controlled machines.

The invention is usefully employed, for example, in connection with a coin-controlled machine of the general construction illustrated in the pending application of Fred L. Mills, Serial No. 738,831, filed September 20, 1924.

10 The primary object of the present invention is to provide a simple device which will operate as a safety feature in the event that an effort is made to cheat the machine, as by subjecting the machine to a jarring action at 15 a time when the latching levers of the pay-out slides are free from engagement with the slides to permit the coin-controlled mechanism to effect release of such pay-out slides as are to operate in effecting discharge 20 of coupons.

The safety catch employed in the present invention operates to catch the pay-out slides in a partly retracted position in the event that the machine is subjected to such 25 jarring action as to effect release of the latching levers in an effort to cheat the machine. The result which is accomplished is to prevent jamming of the coupons and consequent inoperativeness of the machine 30 which might otherwise occur when the pay-out slides are being moved to their normally advanced position in the operation of the machine.

The safety catch of the present invention 35 is especially valuable when used in connection with the fraud-preventing device disclosed in U. S. application 5,508, filed January 29, 1925.

The application just referred to discloses 40 the use of an auxiliary slide disposed below the pay-out slides and normally set in a position which permits coupons to be discharged by the pay-out slides, and discloses, further, an inertia-operated latch-member 45 holding the auxiliary slide normally in the non-obstructing position. When the coin-controlled machine is subjected to such jarring action as will throw the latching levers of the pay-out slides to a free position, the latch-member of the auxiliary slide is, at 50 the same time, thrown to the released position, thereby permitting the auxiliary slide

to be moved by a spring to a position where it will obstruct the discharge of coupons from the pay-out slides. 55

In accordance with the present invention, a safety catch for the pay-out slides is, at the time of such jarring action, thrown to position to catch the pay-out slides in partially retracted position, so that the coupons 60 in the coupon magazine, for example, will partially overlap the coupons in the pay-out slides, and thus, when the pay-out slides are again moved to their normally advanced position, jamming of the coupons will not 65 occur.

The present invention is illustrated in its preferred embodiment in the accompanying drawings, in which—

Fig. 1 represents a broken vertical sectional view of a coin-controlled machine of the character mentioned, equipped with the improved safety lock associated with the fraud-preventing device mentioned, the section being taken approximately as indicated 70 at line 1—1 of Fig. 2; Fig. 2, a broken plan sectional view taken approximately as indicated at line 2—2 of Fig. 1; Fig. 3, a broken plan sectional view corresponding with Fig. 2, but showing the pay-out slides partly retracted but caught and held by the safety lock device; and Fig. 4, a broken vertical sectional view taken as indicated at line 4 of 75 Fig. 3.

It is usual, in the type of machine referred to, to employ a stack of slides, the operation of which is controlled by the coin-controlled mechanism in a manner now understood in the art. The slides are provided with perforations, or chambers, which register with the lower end of a coupon magazine, or a check magazine, and the slides serve, in the operation of the machine, to transfer checks, or coupons, and effect their delivery to a discharge chute with which the machine is equipped. The fraud-preventing device mentioned above comprises an auxiliary slide interposed between the stack of pay-out slides referred to and the passage leading to the discharge-chute. This auxiliary slide is provided with a perforation which registers normally with the discharge passage which extends through the bottom on which the stack of slides is mounted. It is so con- 80 85 90 95 100

trolled that if an effort is made to "cheat" the machine by jarring or jiggling the machine, the auxiliary slide will operate as a shutter to close the discharge passage. Such jiggling of the machine may occur, for example, when an effort is being made to employ a bogus coin, or to employ a penny, where a coin of larger denomination is required, to operate the machine. The safety catch of the present invention is illustrated in the accompanying drawings as comprising a pivotally mounted bent lever associated with the coin-controlled mechanism of the machine in a manner to be presently described.

In the construction illustrated, A designates the casing of a coin-controlled machine which is provided with a base A' and which is equipped at its front with vertical commodity compartments A² (one shown); B designates a frame mounted in the casing and constituting a support for the coin-controlled mechanism B'; and C designates an ejecting device for effecting delivery of articles from the compartments A².

The coin-controlled mechanism controls, in a known manner, the operation of a stack of pay-out slides D which are mounted on a bottom D' which is supported at a suitable distance above the bottom of the casing. The bottom D' is provided with a discharge passage 1 which communicates with the upper end of a discharge chute 2 which extends beneath the ejecting device C to a tray 3 which is open at the front of the machine. The chute 2 is equipped with a shutter 2^a which opens at the proper time to permit the contents of the chute 2 to pass to the tray 3. The shutter 2^a constitutes no part of the present invention.

The pay-out slides D are provided with vertical perforations 4 which normally register with the lower end of the coupon magazine 5. The lowermost one of the slides 45 D is equipped with an upturned arm 6 which is adapted to engage the rear ends of the superposed slides. The slides are moved forwardly to the position shown in Fig. 1 by means of a plunger 7 which is actuated by an arm 8 mounted on a rock shaft 9. The rock shaft 9 is controlled and actuated in a well-known manner in the operation of the machine.

The pay-out slides have connected therewith a series of coil springs 10 which tend to move the slides rearwardly so as to bring the passages, or perforations, in the slides into registration with the discharge passage 1. The pay-out slides are latched in their forward position by latch-levers 11 which are mounted on a vertical pivot 12. The latch-levers 11 normally are held in the latching position by springs 11^a. These latch-levers, or certain of them, may be thrown away 65 from the latching position by means of

throw-out levers 13 which are controlled in a known manner. The pay-out slides are actuated from the bottom slide upward by means of the springs 10, when the corresponding latch-levers 11 are released from engagement with the slides.

The fraud-preventing device mentioned above comprises an auxiliary slide 14 interposed between the lowermost pay-out slide and the bottom D', said auxiliary slide being provided with a perforation 14^a which registers normally with the perforation 1. A spring 14^b (Fig. 3) tends to draw the auxiliary slide 14 rearwardly. An auxiliary latching lever 15, pivoted at 15^a and equipped with a spring 15^b, normally prevents the auxiliary slide 14 from moving rearwardly. The spring 15^b is a delicate one; and, in the event that the machine should be jarred, or jiggled, in an effort, for example, to introduce a penny past the guard devices with which the coin-chute of the machine is equipped, where the machine requires a coin of larger denomination, the spring 15^b will permit the latch 15 to move as a result of the jarring action and release the auxiliary slide 14. The spring 14^b will then draw the slide 14 rearwardly and bring a solid portion of the slide into position to obstruct the upper end of the passage 1. Hence, if a pay-out slide, or a plurality of pay-out slides, should be operated as a result of the fraudulent introduction of a coin of improper denomination, the pay-out slides, nevertheless, would be unable to discharge the checks, or coupons, through the passage 1, and thus cheating of the machine would be avoided.

In Fig. 2, there is shown a supplemental latching device 16 for the pay-out slides, this device being mounted on a lever 16^a. This device constitutes a portion of the coin-controlled mechanism and operates in a well understood manner. It may be stated, however, that when the rock-shaft 9 is turned in the direction indicated by the arrow in Fig. 1, an arm 17 which depends from the rock-shaft engages a spring-held lever 18 mounted on a shaft 19 which drives a gear-train 20 with which is connected a vane 21. The lever 18 is connected by means of a link 22 with the lever 16^a and operates to move the lever 16^a forwardly in a well known manner when the rock-shaft 9 is turned in the direction indicated by the arrow in Fig. 1. A spring 23 serves to return the lever 18 to its normal position and retract the lever 16^a. When the lever 18 swings in the direction indicated by the arrow in Fig. 2, a ratchet device (not shown) permits the lever to move idly with relation to the gear-train 20; and, when the lever 18 is retracted by the spring 23, the gear-train is actuated so as to turn the vane 21 and retard the return (rearward) movement of the lever 16^a.

The ejecting device C is of the rotary type. It is ordinarily actuated by means of an external knob (not shown) applied to the projecting end of its shaft. The actuation of the ejector is controlled by a latch device 24 which is, in turn, controlled by the coin-controlled mechanism. The latch device 24 forms no part of the present invention and need not be further described.

- 10 In accordance with the present invention, the safety catch device E is associated with the pay-out slides and co-acts with the auxiliary latch 16. The member 16 is in the form of a bell-crank lever which is pivotally connected at 25 with the free end of the lever 16^a. The forwardly directed arm of the member 16 has its front extremity 16^b adapted to engage the upturned flange 6 of the lowermost pay-out slide after the slides 20 have been moved forwardly by the push-rod 7 during the first portion of the operation of the coin-controlled mechanism. The member 16 also has a short arm 16^c with which is connected a coil spring 26 which tends 25 to throw the member 16 to the latching position.

The safety catch E is pivotally mounted on the frame at 27 and extends forwardly from the pivot. At its front end, the member E is provided with a lateral catch-arm 28 which is adapted to extend across the path of the pay-out slides and catch the slides in partially retracted position. In front of the pivot 27 the member E is provided with a lug 29 which is adapted to be engaged by the short arm 16^c of the member 16. The spring 26 has one end connected with the arm 16^c, and the other end connected with the lever 16^a. When, in the operation of the coin-controlled mechanism, the push-rod 7 shoves the pay-out slides to their normally advanced position, the member 16 is caused to turn about its pivot 25, and the free extremity 16^b is caused to engage the rear wall of the upturned flange 6 of the lowermost pay-out slide. Thus, the pay-out slides will be held in their advanced position and the latch levers 11 will be relieved from pressure, so that the latch levers, 50 or certain of them, can be thrown into non-engaging position by means of the levers 13, which are controlled by rotating disks (not shown), constituting a portion of the well-known coin-controlled mechanism.

55 The safety catch E lies on the bottom plate of the frame B. A delicate leaf spring 30 which is secured to the frame at a point 31 has its free end normally resting lightly upon the member E, as indicated in Fig. 2.

60 When the machine is jarred, as by tilting it sidewise and striking a lower lateral corner of the machine upon a counter, for example, the safety catch E will be thrown in the direction indicated by the arrow in Fig. 2, 65 thus placing the safety catch in the position

shown in Fig. 3. If, during this jarring action, the pay-out slides, or some of them, are released by reason of the latch members 11 being thrown to the non-retaining position, the springs 10 of the pay-out slides will 70 retract the freed slides, but the slides will be caught in partially retracted position and held by the safety catch E. When the pay-out slides are again moved forward by the push-rod 7, and the pressure of the pay-out 75 slides against the arm 28 is relieved, and the auxiliary latch member 16 is permitted to swing inwardly so as to engage the rear surface of the flange 6, the arm 16^c will engage the lug 29 and swing the safety catch E 80 back to its normal position shown in Fig. 2, it being noted that the spring 26 effects the actuation of the auxiliary latch 16 and through the medium thereof effects the return of the member E to its normal position. 85

Fig. 4 illustrates the position of the pay-out slides D after they have been partially retracted and caught by the arm 28 of the safety catch device E. It is assumed that the jarring action which threw the latch members 11 towards the lateral side of the machine which is depicted at the top of Fig. 3 also threw the auxiliary latch member 15 in the same direction and released the auxiliary slide 14, thereby allowing it to close 90 the discharge-passage 1. It will be noted that the slides D have been caught by the safety catch E in such position that the perforations 4 are partially overlapped by the bore of the coupon magazine 5. Assuming metallic coupons to be contained in the magazine, and in the perforations 4 (although not so shown), it will be understood that the coupons of the magazine will occupy an overlapping relation with respect to the coupons in the perforations 4. Accordingly, when the pay-out slides D are again forced forwardly by the push-rod 7, jamming of the machine will not occur, because the coupons in the perforations 4 will slide readily 100 under the coupons in the magazine. It may happen that some of the pay-out slides will be released from the latch members 11 and retracted, while others may be caught and held by the latch levers 11. In such case, the same overlapping relation of coupons will occur with respect to the coupons contained in the openings 4 of the pay-out slides, 110 so that when any partially retracted pay-out slides are again forced forwardly by the push-rod 7, jamming will be obviated. 115

From the description given, it will be understood that in the normal operation of the machine, one or more of the pay-out slides may be released from the corresponding latch members 11 and may be drawn rearwardly and thus operate to transfer checks, or coupons, to the upper end of the discharge passage 1. In the normal operation, the pay-out slides work from the bot- 120 125

tom up. That is, the lowermost pay-out slides, the lowermost two pay-out slides, etc. may operate. Normally, the auxiliary slide 14 is in such position that the passage 14^a 5 registers with the passage 1. If the machine be jarred, or violently tilted, particularly at a time when the member 16 is holding the pay-out slides and the pressure on the latch members 11 is released to permit one or more 10 of the members 11 to be thrown by the members 13 to the non-latching position, the result will be to cause the delicate spring 15^b to permit the auxiliary latch lever 15 to release the auxiliary slide 14, whereupon the 15 latter will be drawn rearwardly and will then serve as a shutter which closes the passage 1. Consequently, coupons will not be discharged into the chute 2 when the pay-out slides are actuated. Also, in accordance with 20 the present invention, the jarring action which throws the latch members 11 to the non-latching position serve also to throw the safety catch device E in the same direction, and thus place the lateral arm 28 of the device E in position to catch the pay-out slides in a partially retracted position. This insures an overlapping relation of coupons and prevents the machine from becoming jammed when the push-rod 7 returns the pay-out 25 slides to their normally advanced position.

It will be understood from the description given, that the catch member E is actuated by its own inertia, or momentum, when the machine is subjected to jarring action, as by 30 striking the lower lateral edge corner of the machine which appears at the upper portion of Fig. 2 against a counter. That is, under such jarring action, the safety catch is thrown to the latching position where it is 35 in readiness to catch and hold the pay-out slides as they are retracted by their springs.

The foregoing detailed description has been given for clearness of understanding only, and no unnecessary limitations should 40 be understood therefrom, but the appended claims should be construed as broadly as permissible, in view of the prior art.

What I regard as new, and desire to secure 45 by Letters Patent, is:

1. In a machine of the character set forth, the combination with a coupon magazine and pay-out mechanism associated therewith comprising a stack of pay-out slides, springs for actuating said slides, and latch-members 50 associated with said slides, of a safety-catch device lightly held normally adjacent the path of the pay-out slides and adapted to be thrown into the path of the slides in position to catch the slides in partially retracted position when the machine is subjected to jarring action.

2. In a machine of the character set forth, the combination with a coupon magazine and pay-out mechanism associated therewith comprising a stack of pay-out slides, springs

for actuating said slides, and latch-members associated with said slides, of a safety-catch device comprising a pivoted member having an arm disposed normally adjacent the path of the pay-out slides and adapted to swing 70 and thus project said arm into the path of the pay-out slides when the machine is subjected to such jarring action as to throw said latch members to the non-latching position.

3. In a machine of the character set forth, 75 the combination with a coupon magazine and pay-out mechanism associated therewith comprising a stack of pay-out slides, springs for actuating said slides and latch members associated with said slides, of a 80 safety catch device associated with said pay-out slides comprising a pivoted member adapted to be projected into the path of the slides, and a retaining device lightly restraining said pivoted member from movement but permitting said pivoted member to be thrown to the safety position when the machine is subjected to jarring action.

4. In a machine of the character set forth, 85 the combination with a coupon magazine, spring-actuated pay-out slides disposed below said magazine, and latch members adapted normally to hold said slides in registry with the coupon magazine, of a normally retracted inertia-actuated safety catch device 90 associated with said pay-out slides and adapted to be thrown to the safety position in such relation as to catch and hold the slides in partially retracted position when the machine is subjected to jarring action, so 95 that the coupons will occupy an overlapping relation and jamming of the machine will be prevented.

5. In a machine of the character set forth, 100 the combination with a coupon magazine, a 105 stack of pay-out slides disposed beneath said magazine, springs adapted to actuate said pay-out slides, latch members controlling the actuation of said pay-out slides, an auxiliary slide beneath said stack of pay-out 110 slides and normally in position to permit discharge of coupons when the pay-out slides are operated, a spring tending to move said auxiliary slide to an obstructing position, and an inertia-operated latch member holding the auxiliary slide normally in the non-obstructing position, of an inertia-operated safety catch device cooperating with 115 said pay-out slides and adapted to catch and hold the slides in partially retracted position 120 when the machine is subjected to jarring action in an effort to cheat the machine.

6. In a machine of the character set forth, 125 the combination with a coupon magazine, pay-out mechanism comprising a stack of pay-out slides disposed beneath said magazine, springs tending to actuate said pay-out slides, latch members controlling the actuation of said pay-out slides, a device for restoring the pay-out slides to their normal 130

position, and an auxiliary latch device for holding the pay-out slides and permitting freedom of said latch members for an instant during the operation of the machine, of an inertia-operated safety catch device adapted to be thrown into the path of the pay-out slides when the machine is subjected to a jarring action in an effort to cheat the machine, said auxiliary latch device having means for restoring said safety catch device to its normally retracted position.

FRED L. MILLS.
